Franklin A. Kolyer, Murray Hill, N. J., assignor to The Singer Manufacturing Company, Elizabeth, N. J., a corporation of New Jersey

Application July 30, 1956, Serial No. 42,436

Term of patent 14 years

(Cl. D9—2)

Fig. 1.

Fig. 2.

Fig. 1 is a front perspective view of a canister type vacuum cleaner showing my new design.

Fig. 2 is a side elevational view of the canister type vacuum cleaner shown in Fig. 1.

The right rear portion of the canister type vacuum cleaner, not shown in the drawings, is the same as the left rear portion shown in Fig. 2.

The dominant features of my design reside in the portions of the design illustrated in solid lines.

I claim:

The ornamental design for a canister type vacuum cleaner, substantially as shown and described.
